L. W. STUART.
ATTACHMENT FOR CORN PLANTERS.
APPLICATION FILED FEB. 9, 1918.

1,274,954.

Patented Aug. 6, 1918.

UNITED STATES PATENT OFFICE.

LAWRENCE W. STUART, OF ORCHARD, IOWA.

ATTACHMENT FOR CORN-PLANTERS.

1,274,954.

Specification of Letters Patent.

Patented Aug. 6, 1918.

Application filed February 9, 1918. Serial No. 216,368.

To all whom it may concern:

Be it known that I, LAWRENCE W. STUART, a citizen of the United States, residing at Orchard, in the county of Mitchell and State 5 of Iowa, have invented new and useful Improvements in Attachments for Corn-Planters, of which the following is a specification. This invention relates to attachments for corn planters and it has particular reference to an improved device or attachment 10 for raising or lifting the marker from the ground when the machine is being turned at the end of a row, said device being operable by one foot of the operator who will 15 thus be enabled to use both hands for handling the team.

The present invention has for its object to produce a device of the class described which will be simple in construction and capable of being easily installed upon the 20 frame of any ordinary conventional corn planter.

A further object of the invention is to produce a lifting device which when disassembled for shipment will occupy but little space and which may be readily assembled and installed on the frame of a corn planter.

A further object of the invention is to produce a device of the class described, the 30 parts of which will be simple in construction and easily assembled or disassembled.

With these and other ends in view which will readily appear as the nature of the invention is better understood, the same consists in the improved construction and novel arrangement and combination of parts which will be hereinafter fully described and particularly pointed out in the claims.

In the accompanying drawing has been 40 illustrated a simple and preferred form of the invention, it being, however, understood that no limitation is necessarily made to the precise structural details therein exhibited, but that changes, alterations and modifications within the scope of the claims may be resorted to when desired.

In the drawing:

Figure 1 is a perspective view showing the parts of the improved device, including 50 the tubular shaft, the limiting collars, the shaft bearings, the lifting arms, and the marker loop, disassembled.

Fig. 2 is a top plan view showing the rearward portion of a planter frame to

which the invention has been applied and 55 including also the marker.

Fig. 3 is a rear elevation of the same.

Fig. 4 is a side elevation.

Corresponding parts in the several figures of the drawing are denoted by like characters of reference.

The improved appliance or planter attachment includes a tubular shaft 15, bracket members 16 having eyes 17 that constitute bearings for the shaft 15, lifting arms A, 65 one at each end of the tubular shaft, limiting collars 18 whereby the shaft 15 is retained in its bearings, a foot lever B detachably connected with the shaft, and a marker loop 19 adapted to be secured on the 70 staff 20 of the conventional marker which is shown as consisting of a disk 21 associated with the marker staff.

The brackets or bearing members 16 are provided with apertures 22 for the passage 75 of bolts 23 whereby said brackets are secured on the side members 24 of the planter frame from which they extend in a downward direction.

The foot lever B, which is suitably shaped so as to extend across the 80 rearward cross bar 25 of the planter frame, is provided with a clamp 26 engaging the shaft 15, said eye having a bolt 27 for holding the foot lever securely in adjusted position. The bracket members 16 having 85

been mounted on the planter frame, the shaft 15 is passed through the eye or bearing 17 of one of said bracket members; the foot lever B is then placed on the shaft and the latter is now passed through the bearing of the other bracket member. The limiting collars 18 are now placed in position adjacent to the outer faces of the bracket members 16 and the foot lever may now be 90 properly adjusted and secured.

Each of the lifting arms A is curved so as to extend beneath the marker staff 20 and each of said lifting arms has a terminal clamp 28 provided with a bolt 29 whereby it may be secured in position. Each lifting arm has a terminal finger 30 and a lug 31 extending approximately at right angles to said finger. Secured on the marker staff is the loop or keeper 19 which receives the finger 30 of one of the lifting arms, the lug 100 105 31 serving to limit the extent to which the finger 30 will extend through the loop 19.

The parts are obviously to be so propor-

tioned and arranged that when properly assembled and applied to a planter, with the loop of the marker staff engaging the finger 30 of one of the lifting arms, the 5 marker disk 21 will be in ground engaging position. When the machine is to be turned at the end of a row, the operator, by depressing the foot lever B, will rotate the rock shaft 15 in its bearings, thereby lifting the 10 marker clear of the ground and holding it in this position until the machine has been turned.

The marker, which is connected with the 15 frame of the machine in the customary manner by a joint 32, will now be swung manually or in any convenient well known manner into engagement with the lifting arm at the opposite side of the machine.

The improved lifting device for markers, as seen from the foregoing description, 20 is extremely simple in its construction and is capable of being supplied in disassembled condition, permitting the parts thereof to be packed in small compass. The parts, 25 moreover, are of such a nature as to enable the device to be very easily and quickly installed on the frame of any ordinary corn planter.

Copies of this patent may be obtained for five cents each, by addressing the "Commissioner of Patents, Washington, D. C."

Having thus described the invention, what is claimed as new is:

1. A lifting device for planter markers, comprising bracket members having eyes forming bearings, a shaft supported in said bearings, limiting collars on the shaft adjacent to the bearings, a foot lever mounted adjustably on the shaft intermediate the bearings, and lifting arms mounted on the ends of the shaft, in combination with a supported marker staff having a loop for engagement with one of the lifting arms. 40

2. The combination with a planter frame, of a marker staff having a loop secured thereto, bearing members secured on the planter frame, a shaft in said bearing members, a foot lever on the shaft intermediate the bearing members, and lifting arms mounted on the ends of the shaft, each of said lifting arms having a terminal finger for engagement with the loop of the marker staff, and a lug forming an offset whereby the engagement of the loop on the marker staff with the finger of the lifting arm is limited. 50

In testimony whereof I affix my signature.

LAWRENCE W. STUART.
